UNITED STATES PATENT OFFICE.

ANDREW L. UNDELAND, OF OMAHA, NEBRASKA.

BARBER'S CHAIR.

1,116,515.

Specification of Letters Patent.

Patented Nov. 10, 1914.

Application filed November 22, 1912. Serial No. 733,015.

To all whom it may concern:

Be it known that I, ANDREW L. UNDELAND, a citizen of the United States, and a resident of Omaha, in the county of Douglas and State of Nebraska, have invented 5 certain new and useful Improvements in Barber's Chairs, of which the following is a specification.

My invention relates to chairs of the class 10 employed by barbers, dentists, etc., and particularly to those in which the raising and lowering of the chair are controlled by hydraulic pressure.

It is the object of my invention to provide 15 a simple, durable and relatively inexpensive mechanism for operating such chairs, the mechanism being such that the raising, lowering, revolving and reclining may all be controlled by a single operating-lever.

Constructions embodying my invention 20 are illustrated in the accompanying drawings, in which—

Figure 1 is a side view of a chair provided 25 with the improved mechanism, a portion of the seat-base being broken away to show the recline-clamp, Fig. 2 is a vertical sectional view of the operating mechanism, the section being transverse to the operating-shaft, Fig. 3 is a vertical section through the 30 axis of the operating-shaft, Fig. 4 is a detail section in the same plane as Fig. 3, Fig. 5 is a detail section in the same plane as Fig. 2, Fig. 6 is a detail side view of the recline-clamp, Fig. 7 is an end view of the 35 same, Fig. 8 is a section thereof on the axis of the lock-rod, Fig. 9 is a detail of one of the parts of the clamp, Fig. 10 is a detail section of the pump-piston and a part of the plunger, the parts being in the same position 40 as in Fig. 4 but the plane of section being at right angles thereto, Fig. 11 is a horizontal section of the plunger at the locking-plug, and Fig. 12 is a horizontal section of the piston and plunger, on the plane of the lines 45 $x-x$ of Figs. 4 and 10.

The chair illustrated in Fig. 1 is of the type ordinarily used by barbers, and has a suitable base 1 with a column 2 inclosing the hydraulic cylinder 3. The plunger 4, 50 which is movable vertically and rotatably within the cylinder, supports the chair-seat 5. To the seat frame are pivotally connected the back 6 and foot-apron 7, and these are pivotally connected with opposite 55 ends of the arm-rests 8, so that in reclining the chair they move simultaneously toward

a horizontal position. The recline lock-rod 9 is pivotally connected with the foot-apron, as shown, and extends rearwardly through a clamping device disposed at the side of the plunger-head 10 and carried on the end-portion of the crank-shaft 11. The crank-shaft is rotatably mounted in the plunger-head, and at the end opposite the clamping device carries the operating-lever 12. On 60 the central part of the shaft is secured a crank 13, and a connecting-rod 14 extends from the crank-pin down through the plunger and is pivotally connected with the slotted head 15 of the pump piston-rod 16. 65 The piston 17 fits slidably within the bore of the plunger and is fixedly secured upon the piston-rod, being held against a shoulder thereon by means of a nut 18 screwed upon the reduced portion of the rod. The 70 portion of the piston-rod between the piston and the rod-head 15 passes slidably through a cylindrical body 19 which fits slidably within the bore of the plunger and serves as a guide for the piston-rod, as well as for certain other purposes to be hereinafter 75 described. A pin 20 secured to the piston extends up through the body 19 and serves to prevent rotation thereof about the piston rod, while permitting relative longitudinal 80 movement of said parts. The piston has several vertical ports through it, which are normally closed by the plate-valve 21, the latter being held yieldably against the bottom of the piston by means of springs 22 85 placed around studs 23 which are secured to the piston and extend through openings in the valve-plate, as shown in Fig. 4. Upon the bottom of the plunger is secured a head 24 which has an opening therein normally 90 closed by a valve 25. The valve is pushed yieldingly upward by a spring 26 of which the lower end bears against a cross-bar 27, arranged as shown, the valve having a downwardly extending stem thereon which passes 95 through the spring and is guided in the cross-bar.

When the parts are in the positions shown in Fig. 2 the piston is at its highest position relative to the plunger, and the operating-lever is at its extreme forward position, or so that the center-line of the lever is on the dotted line a of said Fig. 2. From this position the lever may be moved rearwardly, past the positions b , c , d and e to the extreme rearward position f , at which the piston will be at its lowest position relative to 105 110

the plunger, or, as shown in Fig. 3. On approaching the latter position a pin 28, integral with the piston-rod and extending below the nut 18, engages the valve 25 and pushes it downward against the spring 26 so that the valve is held open. At about the same time that the valve begins to be opened the upper edge of the piston passes below the upper end of a by-pass groove 29 formed in the wall of the plunger near the head 24. When in this position the liquid in the cylinder 3 may pass through the valve 25 into the plunger below the piston, thence through the by-pass groove and above the piston, thence through one of two transverse ports 30 in the body 19, and upward through one of two vertical ports 31 formed in said body and connecting with the ports 30, as shown in Fig. 10. A passage being thus completed from the cylinder to the interior of the plunger above the piston, the weight of the chair may force the plunger down into the cylinder until the plunger-head engages the seat therefor at the top of the cylinder, as shown in Fig. 3. When the operating-lever is moved forwardly beyond the position *e* the piston is raised to a position such that the upper edge thereof is above the by-pass groove 29, and the pin 28 passes out of engagement with the valve 25, allowing the valve to close. Continued upward movement of the piston then causes the plate-valve 21 to open and the liquid in the upper part of the plunger to pass down through the ports 31 in the body 19, and through the valve-ports into the space below the piston. Downward movement of the piston will then force the liquid through the valve 25 into the cylinder 3 below the plunger so that the plunger will be thereby forced upwardly in the cylinder. The chair is thus elevated by oscillating the operating-lever between the positions *d* and *e* shown in Fig. 2, and is lowered by moving the lever rearwardly beyond the position *e*. When the lever is at the position *d* the piston is at the position shown in Fig. 5 and the lower edge thereof passes above the lower edge of the ports 32 which are formed in the sides of the plunger and coincide circumferentially with the ports 30 in the body 19. During any movement of the piston above the position shown in Fig. 5, the said ports 32 and the ports 30 and 31 form a by-pass around the piston, so that no pumping action can occur. Thus the movement of the operating lever in either direction between the positions *d* and *e* will neither raise nor lower the chair, and such movement may be designated as the "dead-stroke" of the lever and piston, with reference to the pumping action. The said dead-stroke of the operating-lever is utilized for locking the plunger to prevent rotation thereof in the cylinder, for releasing the same, and for releasing the clamping device or recline-lock to per-

mit the chair to be tilted to various positions.

In the side of the plunger is a radial cylindrical opening in which is slidably disposed a cylindrical plug 33 of which the outer end is rounded so as to fit against the wall of the cylinder 3, and its inner end is beveled or inclined toward the lower side. The plug is retained in position by means of a circular spring 34 which lies in a circumferential groove in the outer surface of the plunger, and of which the ends enter recesses in the sides of the plug, as shown in Fig. 11. On the side of the body 19, and at a position thereon coincident circumferentially with the plug, is a beveled face 35 which is adapted to fit against the beveled inner end of the plug 33. When the operating-lever is moved to the extreme forward position *a*, and the piston thus raised to its highest position relative to the plunger, the said beveled face 35 engages the plug and forces it outwardly so that it presses against the side of the cylinder 3. The plunger at the same time is pressed against the opposite side of the cylinder and is thus securely held against rotation therein. After the body 19 has been raised to a position such that it will operate the plug 33, it will tend to remain in said position on account of the frictional engagement between it and the walls of the plunger and end of the plug. However, when the operating-lever is moved rearwardly to the position *c* the piston and piston-rod are moved downwardly to the position shown in Fig. 4, at which the head 15 of the piston-rod engages the body 19 and by pressing the same downwardly releases it from engagement with the lock-plug. Thus, movement of the lever to the position *a* causes the plunger to be locked and held against rotation in the cylinder, and after being locked the same is retained as long as the lever is not moved rearwardly beyond the position *c*.

The clamping device for the recline lock-rod is shown in detail in Figs. 6 to 9, inclusive. The clamp device has an upper part 36 and a lower part 37 which fit around the respective sides of the rod 9, and are pivotally connected with each other by a pin 38 extending parallel to the rod. At the side opposite the pivot-pin 38 studs 39 are screwed into lugs on the lower part 37 and extend upward through corresponding lugs on the upper part 36. Helical springs 40 are disposed around said studs, being normally under compression and pulling the clamp parts toward each other so that they frictionally engage and clamp the rod 9. Lugs 41, integral with the lower clamp part 37, extend upwardly therefrom on opposite sides of the rod 9; and the shaft 11 passes revolvably through the upper parts of said lugs. On the upper clamp-part 36 is an

arch-portion 42 which straddles the shaft 11 between the lugs 41. Through the upper end of said arch-portion is passed an adjusting-screw 43 provided with a lock-nut 44, and of 5 which the lower end is rounded and engages the rocking-block 45. The rocking-block is retained within the arch-portion 42 by means of a pin 46, which passes loosely through a transverse opening in the block, and of 10 which the ends are secured in the arch. The block is normally pushed toward one side of the arch by means of a spring 47 disposed around the pin 46. The lower side of the rocking-block is rounded and rests within 15 a shallow circumferential groove 48 formed in the shaft 11, as shown in Fig. 8, the said part of the shaft forming in effect a cam for actuating the block. During rotation of the shaft corresponding to movement of the 20 operating-lever between the positions *b* and *f*, the rocking-block is not moved, but as the lever is moved forwardly at about the position *b* the higher part of the cam-surface engages the rocking-block and rolls it toward the opposite side of the arch from its 25 normal position. At the same time the block is slightly raised and spreads the clamp-parts 36 and 37 by pressing upwardly on the arch-portion of the part 36 while the shaft 30 presses downwardly on the part 37. A very slight spreading of the clamp-parts is sufficient to enable the rod 9 to slide through them and the inclination of the chair to be varied. The exact position of the operating-lever at which the clamp will be released varies somewhat, owing to the variation in 35 the position of the rod 9 relative to the shaft 11, as will be apparent by reference to the dotted lines in Fig. 1. The rolling movement of the block 45 reduces to a minimum the wear of the cam surface on the shaft, and by adjustment of the screw 43 any wear may be compensated or the parts adjusted so that the spreading of the clamp will be 40 properly timed with relation to the movement of the shaft.

From the foregoing it will be obvious that the entire control of the chair movements may be readily effected by means of the one 50 operating-lever and without the use of other rods, catches or releasing devices. The chair may be raised or lowered to the desired height, then rotated to the desired position and secured in said position by pushing the 55 lever forward to the extreme position. At the same time that the chair is locked against rotation the recline-clamp is released and the chair may be inclined to the proper or desired position. The lever is then moved 60 rearwardly to permit the closing of the recline-clamp and the chair will then be held in the desired position until the lever is again moved. Should it be desired to again change the inclination of the chair without 65 releasing it for rotation, the same may be

done by again pushing the lever forward. Should it be desired to rotate the chair without changing the inclination or the height thereof, the lever is moved rearwardly to the position *c* so as to release the lock-plug, the 70 chair then turned to the desired position, the lever pushed forward far enough to again operate the rotation-lock, and then returned to a position anywhere between *b* and *c*. It should be noted that before any elevation or 75 lowering of the chair can be effected it is necessary that the recline-clamp be permitted to operate and that the rotation-lock be released. It is thus impossible to deface 80 the inner surface of the cylinder by forcibly raising or lowering the plunger while the locking-plug is held in engagement with the cylinder wall.

Now, having described my invention, what I claim and desire to secure by Letters Patent is:

1. In a chair of the class described, a cylinder, a hollow plunger movable vertically and rotatably therein, a pump-piston reciprocatable within the plunger and adapted 90 to force fluid from the plunger into the cylinder, there being a by-pass to permit fluid to pass around the piston during part of its stroke, a locking-plug disposed in the plunger and engageable with the cylinder 95 to prevent rotation of the plunger therein, and a body fitting slidably within the plunger adjoining the piston and actuated by the piston during its movement adjacent to the by-pass for moving the locking-plug 100 into engagement with the cylinder and releasing it therefrom.

2. In a chair of the class described, a cylinder, a plunger movable vertically and rotatably therein, a pump-piston reciprocatable within the plunger, a body vertically 105 slidably within the plunger adjacent to the piston and actuated by movement of the piston beyond predetermined limits, and a plug 110 actuatable by said body to hold the plunger against rotation within the cylinder.

3. In a chair of the class described, a cylinder, a hollow plunger movable vertically and rotatably therein, a plug extending and movable radially through the wall of the 115 plunger, an annular flexible retaining member having its ends engaging the plug and lying within a groove extending around the plunger, and means for moving the plug 120 outwardly to engage it with the cylinder.

4. In a chair of the class described, a cylinder, a hollow plunger movable vertically and rotatably therein, a pump-piston movable within the plunger, an operating shaft 125 connected with the piston for reciprocating the same, a body slidably connected with the piston and fitting within the plunger adjacent thereto, a plug movable radially of the plunger to engage the cylinder and lock 130 the plunger therein, the said slidably body

being engageable with the plug to actuate the same, the body being actuated by movement of the piston beyond predetermined limits, a recline locking device, and means 5 on the operating shaft for releasing said device when the shaft is turned so as to move the piston and the slidable body to engage the latter with the plug.

5. In a chair of the class described, a cylinder, a plunger movable vertically and rotatably therein, a piston slidably disposed within the plunger, a piston-rod secured to said piston, a guide-body fitting slidably within the plunger adjacent to the piston 10 and around the piston-rod, there being abutments carried by the piston-rod to limit relative movement of the piston and said guide-body, a crank-shaft carried on the plunger and connected with the piston rod, 15 valves arranged on the piston and in the end of the plunger to control the passage of fluids through the same, whereby reciprocation of the piston will force fluid from within the plunger above the piston into the cylinder below the plunger, means on the piston 20 for holding open the valve in the plunger, means forming a by-pass around the piston at each end of its stroke, means actuated by the guide-body for holding the plunger 25 against rotation within the cylinder, a recline lock device, and means on the crank-shaft for releasing said device.

6. In a chair of the class described, the combination with a cylinder, a plunger fitting slidably and rotatably therein, a piston fitting within the plunger, a crank-shaft connected with the piston, valves carried by the piston and plunger and controllable by piston-movements to raise and lower the 30 plunger in the cylinder, a recline-lock, and means on the crank-shaft for releasing said lock, of a guide-body fitting slidably within the bore of the plunger adjoining the piston,

a plug extending through the wall of the plunger and actuatable by said guide-body 45 to engage the cylinder and prevent rotation of the plunger therein, and means including the piston engageable with said guide-body to move it into and out of engagement with the plug, said means being arranged to permit free movement of the piston and crank-shaft past the recline-lock-release position while the guide-body is in engagement with the plug.

7. In a chair of the class described, the combination with a cylinder, a plunger working therein, a piston working in the plunger, operating means for moving the piston relatively to the plunger, means controlled by piston-movements for raising and lowering the plunger in the cylinder, and means enabling a dead-stroke of the piston wherein the movements thereof will not affect the relation of the plunger and cylinder, of a locking-plug carried by the plunger and engagable with the cylinder to prevent relative rotation of the plunger and cylinder, a plug-actuating member slidable in the plunger, and means connecting said member in a limited slidable relation to the piston, so that said member will be moved to locking position by movement of the piston to one limit of its dead-stroke, will remain fixed at said locking position during subsequent movements of the piston intermediate 70 of the limits of the dead-stroke, and will be released from said locking position only by movement of the piston to the other limit of its dead-stroke.

In testimony whereof I have hereunto 80 subscribed my name in the presence of two witnesses.

ANDREW L. UNDELAND.
